(57) **CLAIM**

I claim the ornamental design for a utility knife, as shown and described.

DESCRIPTION

FIG. 1 is a bottom, right perspective view of a utility knife, embodying the new design;

FIG. 2 is a bottom, left perspective view of the claimed design of FIG. 1;

FIG. 3 is a right side view of the claimed design of FIG. 1;

FIG. 4 is a left side view of the claimed design of FIG. 1;

FIG. 5 is a top view of the claimed design of FIG. 1;

FIG. 6 is a bottom view of the claimed design of FIG. 1;

FIG. 7 is a front view of the claimed design of FIG. 1;

FIG. 8 is a rear view of the claimed design of FIG. 1;

FIG. 9 is a cross-section view of the claimed design of FIG. 1 taken along line 9-9 in FIG. 4;

FIG. 10 is a bottom, right perspective view of the utility knife of FIG. 1, but illustrated using a wire frame line technique;

FIG. 11 is a bottom, left perspective view of the claimed design of FIG. 10;

FIG. 12 is a right side view of the claimed design of FIG. 10;

FIG. 13 is a left side view of the claimed design of FIG. 10;

FIG. 14 is a top view of the claimed design of FIG. 10;

FIG. 15 is a bottom view of the claimed design of FIG. 10;

FIG. 16 is a front view of the claimed design of FIG. 10;

FIG. 17 is a rear view of the claimed design of FIG. 10; and,

FIG. 18 is a top, right perspective view of another embodiment of the claimed design.

The broken lines depict portions of the utility knife in which the design is embodied that form no part of the claimed design.
